UNITED STATES PATENT OFFICE

152,755

DESIGN FOR A SHOE

David Teitelbaum, New York, N. Y., assignor to Lasting Shoe Co. Inc., Brooklyn, N. Y., a corporation of New York

Application October 11, 1948, Serial No. 149,074

Term of patent 7 years

(Cl. D7—7)

To all whom it may concern:

Be it known that I, David Teitelbaum, a citizen of Poland, residing at New York, in the county of New York and State of New York, have invented a new, original, and ornamental Design for a Shoe, of which the following is a specification, reference being had to the accompanying drawing, forming part thereof.

I claim:

The ornamental design for a shoe, as shown.

DAVID TEITELBAUM.
